UNITED STATES PATENT OFFICE.

CHARLES E. GODLEY, OF DETROIT, MICHIGAN, ASSIGNOR TO THE EDMUNDS & JONES MFG. CO., OF DETROIT, MICHIGAN, A CORPORATION OF MICHIGAN.

COAL-OIL BURNER.

1,082,514.

Specification of Letters Patent. Patented Dec. 30, 1913.

Application filed August 9, 1911. Serial No. 643,212.

To all whom it may concern:

Be it known that I, CHARLES E. GODLEY, a citizen of the United States, residing at Detroit, in the county of Wayne, State of Michigan, have invented certain new and useful Improvements in Coal-Oil Burners; and I do declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to an oil burner for lamps, especially designed for automobile use but adaptable for other purposes, and consists in the construction and arrangement of parts hereinafter more fully set forth 20 and pointed out particularly in the claim.

The object of the invention is to produce a burner of the character described of simple and inexpensive construction wherein the arrangement is such as to cause a strong flow 25 of oil through the wick to supply the flame; to gasify the oil by the presence of heat at the point of combustion, and to hold the center of the flame down substantially on a level with the ends or terminals thereof to 30 obviate smoking and to render the flame broad compared with the width of the wick.

The above object is attained by the structure illustrated in the accompanying drawings, in which:—

35 Figure 1 is a view partly in section showing my improved burner mounted in an oil font. Fig. 2 is a plan view of the burner and font. Fig. 3 is a central vertical section through the burner. Fig. 4 is a sectional view through the burner wick tube at right angles to Fig. 3.

Referring to the characters of reference, 1 designates the tapered stem of the burner which is adapted to enter a correspondingly 45 tapered seat 2 depending from the top of the oil font 3, the burner being locked in position in said seat by reason of the lugs 4 on the stem thereof, which engage in slots 5 in the burner seat. Passing through the

stem of the burner is a wick tube 6 into which 50 project the ratchet wheels 7 on the shaft 8 journaled in the burner stem and carrying on its outer end the knurled thumb wheel 9. The wick 10 passes through the tube 6 and projects from the upper end of said tube 55 into the fitting 11 carried thereby and formed of relatively thick metal to afford the necessary heat retaining quality. This fitting is crescent shaped and is concavo-convex in cross section, the terminals thereof 60 describing outwardly and upwardly projecting prongs 12 which extend well beyond the edges of the wick tube and above its upper end. The crescent shaped fitting 11 is provided at the center with an upwardly projecting finger 13 on each side thereof, said fingers curving inwardly above the upper end of the wick tube.

Upon lighting the burner the fitting 11, which is in effect a flaring enlargement of 70 the upper end of the wick tube, becomes intensely heated and being of considerable thickness the heat is retained so that the presence thereof around the upper end of the wick vaporizes the oil, causing it to burn 75 as a gas above the wick end, obviating to a great extent the charring of the wick and producing a comparatively white flame. The projecting prongs which form a curved trough on each side of the wick tube tend to 80 draw the flame out to a much greater width than in the common burner. The usual tendency in the flame from an oil supplied wick to burn to a point is overcome by the presence of the opposed inwardly bent fingers 85 13, which hold down the flame at the center substantially on a plane with the sides of the flame, thereby obviating smoking. These bent fingers 13 together with the concave fitting serve to hold the flame around the wick, 90 thereby making it difficult to extinguish the flame by a draft or by vibration.

By maintaining a high degree of heat around the upper end of the wick the flow of oil through the wick to the point of combustion is accelerated, thereby obviating burning the wick and insuring a steady and bright flame.

Having thus fully set forth my invention, what I claim as new and desire to secure by Letters Patent, is:—

An oil burner comprising a wick tube, a concavo crescent shaped cup located at the upper end of the said tube, said fitting having opposed slender fingers the ends of which are turned inwardly and adapted to

be heated by the lower edge of the flame produced by the burner.

In testimony whereof, I sign this specification in the presence of two witnesses.

CHARLES E. GODLEY.
